UNITED STATES PATENT OFFICE.

CHARLES M. PERKINS, OF COHOES, NEW YORK.

THREAD-USING MACHINE.

Application filed May 22, 1922. Serial No. 562,799.

This invention relates particularly to an automatic knot and slug detecting and stop motion device for multiple thread machines, wherein provision is made for the automatic 5 operation of stop mechanism for the machine through the presence of a knot or other imperfection in any thread or threads drawn from the spools.

The invention is particularly designed for 10 application to a machine set and maintained in motion through the manual operation and holding of an appropriate treadle or the like, the presence of a knot or similar imperfection in the thread or threads being used, 15 automatically actuating means to disconnect the treadle from operative control of the mechanism, and thereby permit such mechanism to act as a stop motion.

An important object of the present invention 20 is the provision of thread guides, through which the thread passes, and which are adapted to be actuated by the presence of a knot or other imperfection in the thread. These guides are constructed so that one at 25 least is somewhat more sensitive and quickly responsive to thread imperfection than the others, whereby provision is made for taking care of threads having sensitive tension adjustments, as are necessary in some stitching operations.

A further object of the invention is the provision of a release mechanism involving a trip mechanism, the release mechanism provided with normally set for the manual control of ordinary sewing machine stop mechanism, the release mechanism including a trip, which when operated, causes the release mechanism to interrupt the manual control 35 of the stop mechanism, and thereby release 40 the stop mechanism for effective operation. The trip mechanism, which is arranged intermediate the thread guides and trip of the release mechanism, is automatically set in motion by the movement of the thread guide 45 due to a thread imperfection, to operate the trip and set the release mechanism in operation.

The trip mechanism is within control of the manual means through which the machine is normally governed, so that following an automatic action of the trip mechanism, through a thread imperfection, the manually operable means will restore and automatically set the trip mechanism for 50 succeeding automatic control.

An important detail of the present invention

is the arrangement of the trip mechanism, which the thread directly governs for the operation of the release mechanism, so that following automatic action of such 60 trip mechanism, the thread guide is free to continue its movement in the direction of the thread movement, and formed so that in such continued movement, the thread and obstruction thereon is permitted to freely 65 pass the thread guide, thus the thread and obstruction will pass by the thread guide without undue tension on the thread, and there is little liability of thread breakage or disturbance of adjustments resultant from 70 undue tension on the thread.

The release mechanism is adapted to be actuated by the power table shaft, which drives the machine to be stopped, and is thereby instantly responsive to the control 75 resultant from a tread imperfection passing through the thread guide, the parts, following the release movement, tending to resume a normal position in so far as permitted by 80 cooperating parts, to thereby provide for resetting the machine merely through the operation of the foot treadle or the like.

In the drawings:

Fig. 1 is a view in elevation partly in section, illustrating the improvement with 85 the parts shown in connected relation, and the stop motion indicated in release and stop positions in full and dotted lines respectively.

Fig. 2 is a perspective view of the thread 90 guide and trip mechanism controlled thereby.

Fig. 3 is a vertical sectional view partly in elevation of the same.

Fig. 4 is a front elevation of the same. 95

Fig. 5 is an enlarged broken vertical section showing the support for the thread guides.

Fig. 6 is a section on line 6—6 of Fig. 5.

Fig. 7 is a view similar to Fig. 6, the 100 thread guide being shown in position resultant from a knot in the thread, and the catch of the trip mechanism being shown released.

Fig. 8 is a section on line 8—8 of Fig. 5. 105

Fig. 9 is a section on line 9—9 of Fig. 5.

Fig. 10 is a perspective detail showing the means for actuating the thread guides of the plural arrangement through the release of the trip mechanism following the operation 110 of the sensitive thread guide.

Fig. 11 is a view in elevation partly in

section, illustrating the stop motion release means and the connection between the same and the trip mechanism, the parts being in normal positions.

5 Fig. 12 is a similar view with the parts in operative positions, and the connection to the stop motion in release position.

10 Fig. 13 is a perspective view showing the arrangement of the bars connected to the stop motion and to the treadle, the interlocking bar being shown in position to release the stop motion bar.

15 Fig. 14 is a horizontal sectional view illustrating the release mechanism and the connection between the same and the stop motion.

20 Fig. 15 is a broken view in elevation for the trip resetting means, the resetting pawl being shown in initial resetting position in dotted lines.

Fig. 16 is a similar view, the resetting pawl being shown in position assumed immediately following the resetting operation.

25 Fig. 17 is a perspective view illustrating the resetting pawl and guide therefor in relation to the resetting member of the trip mechanism.

Fig. 18 is a perspective view of one wall of the guide for the resetting pawl.

30 Fig. 19 is a perspective view of the resetting pawl and the connection between the same and the operating treadle.

35 The present invention involves the specific construction and the combinative relation of several distinctive instrumentalities, which will be hereinafter described in the order named, and which may be briefly referred to as thread guides, through which the threads pass, and which are operated by any knot or 40 imperfection in any of the threads; a trip mechanism released in the operation of the thread guides for a free operative and preferably gravitational movement; a release mechanism which is brought into operation by and 45 following the operative movement of the trip mechanism and a stop motion of approved or conventional design, which is automatically set in motion to stop the machine through actuation of the release mechanism.

50 The thread guides and trip mechanism are supported above the bed plate of the machine, and comprise a standard 1 rising from said bed plate, to which is secured at the upper end a hollow rectangular frame 2. Ears 3 depend from the respective ends 55 of the frame and rotatably support a trip shaft 4. Collars 5 and 6 are secured in spaced relation upon the shaft 4, from each of which extend tubular projections 7, 60 adapted to adjustably receive, through set screws 8, rods 9. A plate 10 is carried by the upper ends of the rods 9, the upper edge of the plate being formed with V-shaped notches 11.

65 An inverted U-shaped strip 12 is friction-

ally engaged over the upper edge of plate 10, said strip 12 being formed in the lower edges with V-notches 13, cooperating with the notches 11, to thereby form thread openings, through which the thread passes. 70 Plates 10 and 12 are here shown as formed with four thread openings, these plates constituting a thread guide for the reception of a plurality of threads, it being understood of course that any number of thread openings may be formed therein. An additional independent thread guide, designed particularly for more sensitive operation than the thread guides previously described, is also mounted on the shaft 4, and comprises a sleeve 14 freely rotatable on the shaft, from which extends a tubular projection 15 adjustably receiving a rod 16 formed at the upper end with divergent fingers 17, which at their juncture is formed with a slot 18, 85 the width of thread diameter. The sleeve 14 is of reduced diameter at one end as at 19, and this reduced portion is formed in part of a square or plain face 20, to receive the upper laterally projected end 21 of a latch 22. 90 A spring 23 is secured in one of the ears 3 and coiled about and connected to the shaft 4, this spring serving to normally hold the respective thread guides in the upright or operative positions. A rod 24 is secured to 95 one of the tubular projections 7 and extends to and in rear of the projection 15, whereby when the thread guides in the plates 10 and 12 are operated by a knot or other imperfection in the thread, the thread guides 17 will 100 also be operated by the rod 24, though the thread guides 17 may be independently operated by the thread passing therethrough, as will be apparent from the drawings and description. This construction permits the use 105 of the device in a multi-thread machine, of which one particular thread is of such a nature, as by material or required tension, that the means resultant from the attempt of an imperfection in that thread to pass, must be 110 extremely sensitive. The independent thread guide is thus more sensitive than the remaining thread guides.

115 The trip mechanism is controlled by the latch 22 and comprises a rod 25 slidably mounted in guides 26, projecting from the standard 1, the upper end of the rod having a block 27 removably secured thereon by a set screw 28, to which block the latch 22 is 120 removably secured at 29. A weight 30 is adjustably secured upon rod 25 by a set screw 31, this weight causing the rod 25 to move downwardly when the latch 22 is released, the adjustment of the weight providing for 125 limiting this downward movement of the rod to the desired extent through cooperation of said weight in one of the guides 26. The lower end of the rod is provided with a block 32, adjustably secured thereon, and formed with outstanding lug 33, through which is 130

threaded a screw 34. The end of the screw is adapted to engage one end of a lever 35 pivotally supported on a lug 36, rising from the bed plate, the opposite end of the lever 5 having a loose connection with a pull rod 37. The pull rod is adapted to operate the trip lever of the release mechanism to be later described, and the extent of this operation can be readily controlled through adjustment of the screw 34. The block 27 on the upper end of the rod 25 is provided with an upwardly extending member 38 slotted at 39 to receive a pin 40, projecting from a collar 41, secured upon shaft 4. 15 The release mechanism proper is mounted upon a frame fixed to the under side of the bed plate of the machine, and comprises a plate 43 with a depending web 44. A shaft 45 is supported in suitable bearing bosses 20 projecting from the web 44, and is provided at one end with a pulley 46 adapted to be connected by belt 47 operated from a suitable pulley 48 on the power table shaft. The opposite end of the shaft 45 is provided with 25 a serrated or toothed disc 49, which disc from its connection with the shaft, is also continuously operated. Pivotally supported in the web 44 above the shaft 45 is the inner end of a release lever 50, the outer or free 30 end of which pivotally supports at 51 a pawl 52, the tooth formed end 53 of which is in line with the toothed edge of the disc 49. The pawl 52 has an arm extension 54 projecting toward the pivot of the lever 50, this 35 arm extension 54 being connected to the pull rod 37. The pawl 52 is supported upon a stud, which stud has an extension. The end of the stud beyond the pawl is slotted and a spring is coiled about the stud with one end seated in the slot, the opposite end engaging behind the projection. Thus, the spring may 40 be adjusted by turning the stud, a set screw holding the stud in adjusted position. A stop 55' is arranged to limit the distance 45 of the toothed end 53 of the pawl 52 from the disc 49. By turning the head 57, the limit position of the lever is obviously adjustable. The inner or pivotally connected end of the lever has a depending projection 58, which through the medium of a link 59, is connected to an interlocking bar 60, which 50 extends through a suitable guide opening in a bracket 61, secured to or forming part of the release mechanism frame. This bracket 55 61 slidably supports a bar 62, which is directly connected, as through a rod 63, with a treadle or other manual pressure means (not shown). A similar bar 64 is slidably mounted in the bracket 61 and this bar 64 is, 60 through the medium of a rod link 65, connected to the end of arm of a clutch lever of the stop motion to be later referred to.

The pawl 52 is tensioned to insure its proper movement by spring 55'', while 65 spring 55' acts to normally maintain proper

relation between the pawl and lever 50 when the parts are in inoperative positions.

In the normal positions of the parts, the free end of the release lever 50 is resting upon the adjustable stop 57, and the interlocking bar 60 is in normal or operative position. In this position, the said bar extends through an opening 66 in the treadle connected bar 62, and also for an appropriate length into an opening 67 in the 75 clutch lever operating bar 64. Thus with the interlocking bar 60 in normal position, the bars 62 and 64 are actuated as a unit in the depression of the treadle or similar member, but on the withdrawal of the interlocking bar from its connection with the clutch lever operating bar 64, the latter is free to move for a purpose to be hereinafter referred to.

The interlocking bar 60, which is the bar 85 which controls the interlocking cooperation between the bars 62 and 64, permits manual operation of the bar 62, after the bar 64 is freed. This manual operation of the bar 62, which so long as the bars 62 and 64 90 are connected by the interlocking bar 60, serves to start and stop the machine at the will of the operator, is utilized following an automatic action of the stop motion, due to thread imperfection, to reset the parts, and 95 particularly the thread guides and trip mechanism described.

For this resetting of the thread guides and trip mechanism, the bar 62 is connected to a rod 68, which extends through the bed plate of the machine, and is provided with an enlarged end 69, in which is pivotally supported a pawl 70, a spring 71 being coiled about the enlarged end 69 and engaging the pawl to hold the same in substantial alignment with the rod. A pawl guide 72 is mounted on the bed plate to one side of the pawl and has an offset bend 73 therein, so that the upper portion of the guide is vertically offset from the lower portion. The guide includes a plate 74 secured at its upper end to the guide proper and depending from such upper end in spaced relation to the guide proper to provide a channel 75 to slidably receive a pin 76 projecting from the pawl 70. The plate 74 is formed with an opening 77 at the upper limit of movement of the pawl, of a size to permit the pin to pass therethrough, the lower end of the plate terminating above the offset 73 of the guide proper, so as to permit the pin, when riding on the offset, to be guided thereby outwardly beyond the plate 74. The block 32 on the side next the pawl 70, is formed near its upper end with a projection 78 having an undercut bottom wall 79, and the upper end of the pawl is inclined at 80 to correspond with the undercut projection. It 125 may be here stated that in the normal con-

trol by the operator of the starting and stopping of the machine, the lowest limit of movement of the pin 76 is above the offset 73, so that the pin merely reciprocates in the space between the guide proper and plate 74, but that following automatic operation of the stop motion, the pawl is moved to a lower position, so that the pin 76 is guided out by the offset 73, thereby positioning the end of the pawl beneath and interlocking the same with the undercut projection 78 of the block 32. On the upward movement of the treadle, the pawl operates to lift the block 32 and restore the trip mechanism, whereupon the spring 71 restores the pawl to its normal substantially vertical position, disengaging the pawl from the block 32. When the pawl raises the mechanism and the latch 22 properly cooperates with the plain face 20 and maintains this cooperation, the pawl 70 will leave the undercut 78 and through the action of spring 71 return to normal position, the pin 76 riding through the opening 77. If however, due to a too sensitive adjustment or a jar in the operation, the latch 22 does not properly engage the surface 20, the undercut projection 78 will hold the pawl 70 against the action of the spring 71, and as the treadle moves downward, the trip mechanism will follow and thus automatically trip the stop mechanism before the clutch has been engaged. Thus until the operation is such that the latch 22 is properly in position, no starting operation is had. In order that the operation of the mechanism described may be better understood, it is deemed advisable to describe a conventional and well known type of stop motion. This stop motion includes a shaft 81 held against movement in brackets 82 secured to and depending from the bed plate. On this shaft is loosely mounted a clutch member including a clutch face 83, a brake disk 84, secured to such clutch face, a pulley 85, from which a belt 86 extends to operate the particular sewing machine with which the improved mechanism is associated, and a thrust collar 87.

A cooperating clutch member is also mounted on the shaft 81, including a clutch section 88 to cooperate with the clutch face 83, and a connected belt wheel 89 to be operated from the line shaft, which shaft may be common to a number of machines. A lever 90 is pivotally supported on a bracket 91, depending from the bed plate and is provided with an arm 92, carrying a brake member 93 to cooperate with the brake disk 84, a thrust arm 94 bifurcated to straddle shaft 81 and cooperate with thrust collar 87, and an arm 95 projecting oppositely from arm 92 with respect to the pivot. The arm 95 is connected to the bar 64 through the rod link 65 previously referred to. A spring 96 connects the lever 90 with the bed plate, said

spring normally influencing the lever for movement in the direction to apply the brake 93 and release the pressure of the thrust arm 94 on the thrust collar 87 and thereby permit disengagement of the clutch members 70 83-88.

Assuming the parts to be constructed and arranged as described, it is apparent that a knot or other imperfection in the thread passing through any of the thread guides 75 will move said guides in the direction of travel of the thread. If the imperfection exists in the sensitive thread guide 17, this guide will be turned on the shaft 4 as a center until the plain portion 20 of the sleeve extension 19 will ride from beneath the latch 22. This permits rod 25 to move downwardly under the influence of weight 30 and all of its contained parts and exert an upward pull on the connector 37, through lever 35. 80 The downward movement of the rod 25 through member 38 and pin 40, turns the shaft 4 against the tension of the spring 23, thus turning the thread guides in plate 10. If however, the thread having the imperfection is one passing through the thread guides in the plate 10, said guides will be tilted by the thread, and arm 24 will cause a corresponding movement of the thread guide 17, thereby releasing the latch 22 with the result 85 described. As connection 37 is drawn upwardly, the pawl 52 is operated to cause the tooth end 53 thereof to engage one of the teeth of the disc 49. As this disc is continuously operated from the power shaft, 100 the connection of the pawl thereto raises the free end of lever 50 until the arm 54 of pawl 52 engages the stop 97, whereupon the pawl is forced from engagement with the tooth disc. This movement of the lever 50 will, 105 through the link 59, draw the interlocking bar 60 from the bar 64, whereupon the spring 96 immediately acts to free the clutch 83-88 and apply the brake 93. This stops the movement of band pulley 85 and so stops the 110 particular machine.

As the bar 64 is thus moved by the spring 96, the opening 67 therein is out of alignment with the interlocking bar 60, and hence the spring 55, which tends to restore the 115 lever 50 to normal position, cannot fully return said lever. The operator regains control of the machine and simultaneously resets the trip mechanism and thread guides, by moving the operating treadle first downwardly to cause the pawl 70 to lock beneath the offset 78 of the block 32, which block is now of course in lowered position, then moves the treadle upwardly, thereby moving the rod 25 to a position to cause the latch 22 120 to again engage the plain portion 20 of the sleeve member of the sensitive thread guide, and at the same time moving the bar 62, and connected interlocking bar 60 upwardly, until said interlocking bar aligns with the 125 130

opening 67 in the bar 64. The spring 55 then tends, through the lever 50, to move the interlocking bar 60 to engage the opening 67 in the bar 64. The bars 62 and 64 are again connected, whereupon the operator, by the continued movement of the pedal in the downward direction, operates the lever 90 to release the brake 93 and cause the clutch members 83-88 to be engaged through pressure of the thrust arm on collar 87. The machine is thus started, and within complete control of the operator for stopping and starting at will.

It is to be particularly noted that when a thread guide has been operated and the latch 22 released, the thread guide shaft seeks to return to normal position under the influence of the spring 23. This spring however, is insufficient to hold the thread guides in normal position against the continued pull of a thread, and hence following the automatic trip through a knot or other imperfection in the thread, said guides will tilt to a position to permit the thread knot or other imperfection to pass through the guide without a material interruption of the thread movement. This is important as thereby there is little or no interruption to the normal travel of the thread, and hence there has been no undue tension placed upon the thread for the actuation of the released mechanism. The thread guide movement is naturally a sensitive one, and the engagement of the latch 22 is also so delicately balanced that the presence of a knot or other imperfection will cause the necessary release of the trip mechanism entirely without stopping the travel of the thread. The automatic stop motion is thereafter wholly independent of the thread, and hence the thread is not broken nor its tension interfered with in order to secure an operation of the stop motion.

A spring 99 is secured upon a stud 100 on collar 5 which is adjustable on the trip shaft, one end of this spring being arranged in front of one of the tubular supports 7 and the opposite end in front of the tubular support 15 of the sensitive thread guide. In the operation of the sensitive thread guide alone, this spring acts to return said guide to an operative relation to the remaining thread guides.

Claims:

1. A stop member for thread using machines, a separate continuously operated power element, manually operable starting means, a connector between said starting means and stop element to actuate the stop element to release position in the movement of the starting means, a lever for operating the connector, and means carried by said lever and actuated by a defect in the thread of the machine to cause said lever to be operated by the separate continuously operated

power element to move the connector to release the stop means.

2. A stop means for thread using machines, a manually operable starting means, a movable connector between said means, a lever secured to said connector, a power driven toothed disc, a pawl carried by said lever to cooperate with said disc, and means controlled by a thread defect for moving said pawl into cooperation with said disc. 75

3. A stop means for thread using machines, a manually operable starting means, a movable connector between said means, a lever secured to said connector, a power driven toothed disc, a pawl carried by said lever to cooperate with said disc, a lever operated by a defect in the thread, and a connection between said lever and pawl to operate the pawl in the movement of the trip lever, said connection freeing the lever for further movement in the thread feeding direction to release the thread obstruction. 85

4. A stop means for thread using machines, a manually operable starting means, a movable connector between said means, a lever secured to said connector, a power driven toothed disc, a pawl carried by said lever to cooperate with said disc, a lever operated by a defect in the thread, and a connection between said lever and pawl to operate the pawl in the movement of the lever, and means to disconnect the pawl from the disc following a predetermined movement of said lever. 95

5. A stop means for thread using machines, a manually operable starting means, a movable connector between said means, a lever secured to said connector, a power driven toothed disc, a pawl carried by said lever to cooperate with said disc, a lever operated by a defect in the thread, and a connection between said lever and pawl to operate the pawl in the movement of the lever, and means to return said connector to normal position. 100

6. A stop means for thread using machines, a manually operable starting means, a movable connector between said means, a lever secured to said connector, a power driven toothed disc, a pawl carried by said lever to cooperate with said disc, a tripping mechanism operated by a defect in the thread, and a connection between said tripping mechanism and pawl to operate the pawl in the movement of said mechanism, means to return said mechanism to normal position, and an adjustable stop to limit the normal position of the lever. 115

7. In a multi-thread using machine, an automatically operable stop motion, manually operable means for controlling the stop motion, and mechanism whereby the stop motion is released from the manually operable means for automatic actuation by the imperfection of a thread, said mecha- 125 130

nism including a plurality of thread guides movable to set said mechanism in operation when an imperfection in any of the threads in said guides is presented to a guide, one of said guides being more sensitive than the others.

8. In a multi-thread using machine, an automatically operable stop motion, manually operable means for controlling the stop motion, and mechanism whereby the stop motion is released from the manually operable means for automatic actuation by the imperfection of a thread, said mechanism including a shaft, a plural thread guide secured on the shaft, an independent thread guide mounted for free movement on the shaft, and a connection whereby movement of the plural thread guide operates the independent thread guide.

20 9. In a multi-thread using machine, an automatically operable stop motion, manually operable means for controlling the stop motion, and mechanism whereby the stop motion is released from the manually operable means for automatic actuation by the imperfection of a thread, said mechanism including a tripping means operated by gravity to inaugurate the stop motion release, a latch for holding the trip mechanism against the influence of gravity, a multiple thread guide normally engaging said latch, and means to permit movement of the guide to release the latch in the attempt of an imperfection in the thread to 35 pass through said guide.

10. In a multi-thread using machine, an automatically operable stop motion, manually operable means for controlling the stop motion, and mechanism whereby the stop motion is released from the manually operable means for automatic actuation by the imperfection of a thread, said mechanism including a thread guide shaft, a plural thread guide fixed on said shaft, an independent 40 guide mounted on said shaft, a connection whereby movement of the plural thread guide operates the independent thread guide, a tripping mechanism to inaugurate the stop motion release, and a latch cooperating with the independent thread guide to hold the tripping mechanism from operative movement under normal conditions.

11. In a multi-thread using machine, an automatically operable stop motion, manually operable means for controlling the stop motion, and mechanism whereby the stop motion is released from the manually operable means for automatic actuation by the imperfection of a thread, said mechanism including a plurality of thread guides, a trip mechanism released in the thread operation of any of said guides to inaugurate the stop motion release, said manually operable means being movable to regain control of the stop motion following the automatic actuation of

the latter, and means whereby said movement of the manually operable means automatically resets the tripping mechanism in normal relation to the thread guides.

12. In a stop motion for automatically 70 stopping when a defect in the used thread contacts with a detector, tripping means controlled by the detector to stop the thread using mechanism, means for restoring the tripping means to operative position by motion in one direction, a separate means for holding the tripping means in operative position, means for moving the restoring means from the path of the tripping means by a reverse motion of said restoring means, said 80 reverse motion positioning the tripping means to permit continued operation of the thread mechanism.

13. A trip mechanism including an upright, a shaft supported thereon, a series of 85 thread detecting means arranged on said shaft, an operating trip element supported for movement lengthwise the upright, and a latch carried by said element and cooperating with one of said members to hold the trip element against movement.

14. A trip mechanism including an upright, a shaft supported thereon, a series of 90 thread detecting means arranged on said shaft, an operating trip element supported for movement lengthwise the upright, and a latch carried by said element and cooperating with one of said members to hold the trip element against movement, said latch 95 being released by movement of any of said members under a thread defect.

15. A trip mechanism including an upright, a shaft supported thereon, a series of 100 thread detecting means arranged on said shaft, an operating trip element supported for movement lengthwise the upright, and a latch carried by said element and cooperating with one of said members to hold the trip element against movement, said latch 105 being released by movement of any of said members under a thread defect, and manually operable means for moving the element to position the latch in cooperation with said member.

16. A trip mechanism including a movable element adapted at one limit of movement to operate control means, a latch for holding the element against movement, and thread detector mechanism serving when operated to release the latch, said detector mechanism including a plurality of thread 115 receiving elements to be actuated by thread imperfection, one of said elements controlling the latch, the others of said elements 120 controlling the latch through the first mentioned element.

17. A trip mechanism including a movable element adapted at one limit of movement to operate control means, a latch for holding the element against movement, and 125

thread detector mechanism serving when operated to release the latch, said mechanism including a thread imperfection detector directly cooperating with the latch, and an additional thread imperfection detector indirectly cooperating with the latch.

18. A trip mechanism including a movable element adapted at one limit of movement to operate control means, a latch for holding the element against movement, and thread detector mechanism serving when operated to release the latch, said mechanism including a plurality of thread imperfection detector elements, and means to render one of said thread imperfection detecting elements more sensitive to thread imperfection in latch control than the others.

19. A trip mechanism including a movable element adapted at one limit of movement to operate control means, a latch for holding the element against movement, and thread detector mechanism serving when operated to release the latch, said mechanism including a thread imperfection detector adapted for swinging movement under a thread imperfection, and means carried by said detector to engage and support the latch when the detector is in normal position and release the latch when the detector

is in operative position, and additional thread imperfection detectors serving when operated to actuate the first mentioned detector and thereby release the latch.

20. A trip mechanism including a movable element adapted at one limit of movement to operate control means, a latch for holding the element against movement, and thread detector mechanism serving when operated to release the latch, said mechanism including a thread imperfection detector directly controlling the latch, and a second thread imperfection detector adapted in operation to engage and operate the first mentioned detector to thereby control the latch.

21. A trip mechanism including a movable element adapted at one limit of movement to operate control means, a latch for holding the element against movement, and thread detector mechanism serving when operated to release the latch, said mechanism including a thread imperfection detector directly controlling the latch, and another thread imperfection detector having a rod adapted in operation to engage said first mentioned detector to thereby actuate the latch.

In testimony whereof I affix my signature.
CHARLES M. PERKINS. [L.S.]
